COMBINED BLADE RECONDITIONING TOOL AND GLASS CUTTER

Raymond S. W. Lindsay, 1434 Mountain Ave.,
Duarte, Calif.

Filed Jan. 10, 1964, Ser. No. 78,147

Term of patent 14 years

(Cl. D37—1)

FIGURE 1 is a perspective view of a combined blade reconditioning tool and glass cutter embodying my new design;

FIGURE 2 is a top plan view of FIGURE 1;

FIGURE 3 is a longitudinal edge view from the lower edge of FIGURE 2;

FIGURE 4 is a bottom plan view of FIGURE 2; and

FIGURES 5 and 6 are end views of the respective ends of FIGURE 2.

I claim:

The ornamental design for a combined blade reconditioning tool and glass cutter, as shown.
